(57) **CLAIM**

I claim the ornamental design for a latch handle and plate, as shown and described.

DESCRIPTION

FIG. 1. Is a perspective view of my latch handle and plate;

FIG. 2. Is a front view thereof;

FIG. 3. Is a rear view thereof;

FIG. 4. Is a left side elevational view thereof, the right side view thereof is substantially identical hereto;

FIG. 5. Is a top view thereof; and,

FIG. 6. Is a bottom view thereof.

The broken lines are for illustrative purposes only and form no part of the claimed design.
